(57) **CLAIM**

The ornamental design for a display of a handheld terminal with graphical user interface, as shown and described.

DESCRIPTION

The patent or application file contains at least one drawing executed in color. Copies of this patent with a color drawing will be provided by the Office upon request and payment of the necessary fee.

The FIGURE is a front elevational view of a display of a handheld terminal with graphical user interface showing our new design.

The broken lines shown in the Figure represent portions of the display of a handheld terminal with graphical user interface that form no part of the claimed design.
